UNITED STATES PATENT OFFICE.

WILFORD J. HAWKINS, OF NEW YORK, N. Y.

AIR PUMP.

Application filed October 14, 1921. Serial No. 507,603.

To all whom it may concern:

Be it known that I, WILFORD J. HAWKINS, a citizen of the United States, residing at New York, county of New York, and State 5 of New York, have invented a new and useful Improvement in Air Pumps, of which the following is a specification.

This invention relates to an improvement in air pumps designed to be used in connection with an engine cylinder and operated by the pressure from said cylinder to compress air for tire inflation, whistle blowing, etc., and it consists in certain constructions which will be hereinafter fully described 10 and then specifically set forth in the claim hereunto appended.

The accompanying drawing, which forms a part of this specification and in which the like characters of reference indicate the 20 same or like parts, is a sectional elevation of a device constructed in accordance with the invention.

In carrying the invention into effect, there is provided a small air pump having a hollow stem adapted to be screwed into an engine cylinder—for example, in place of a priming cup,—to establish pressure communication between said cylinder and said pump, the operation of the pump being effected by the pressure derived from the engine cylinder. In the best constructions, the device is provided with a cut-off valve 25 operated in the hollow stem and with a priming device in communication with the interior of the stem above the cutoff valve.

Referring to the drawing, 1 indicates a pump cylinder having its lower end closed by an integral head 2 from which depends a hollow stem 3. This stem is provided with an external thread 4 by means of which it 40 may be connected to an engine cylinder 5. Working in the cylinder 1 is a plunger 6 provided with piston rings 7. For the purpose of normally holding the plunger 6 in its lowermost position, as shown in the drawing, there is provided a helical spring 8 bearing against the upper face of the plunger and against a removable cylinder head 9 screwed on the exterior of the cylinder 1 at 10. The cylinder 1 is provided with

a series of inlet ports 11 cut through its wall just above the top of the plunger 6 when in its lowermost position. The cylinder head 9 is provided with a ball check valve 12 held in place by means of a spring 55 13, the upper end of which bears against a plug 14 screwed into the cylinder head 9. The ball check valve operates in a passage 15 of the usual kind, and this passage is in open communication with a transverse passage 16. An air pipe 17 connects with the passage 16 and is held to the cylinder head 9 by means of a union 18 of well known construction.

For the purpose of cutting off communication between the air pump and the engine cylinder 5, there is provided a cutoff valve 19 located in the interior of the stem 3 and operated by means of a handle 20. For the purpose of providing a priming device to be 60 used with the air pump when the latter is used in connection with an internal combustion engine cylinder, a hole 21 is drilled in the closed end of the cylinder 1 to open into the hollow stem 3, and a priming device 22 65 of ordinary construction is screwed to the air pump in operative connection with the hole 21 so that when the cutoff valve 19 is open the engine cylinder can be primed.

When the cutoff valve 19 is open, pressure 70 from the engine cylinder 5 drives the plunger 6 up against the resistance of the spring 8, compresses the air above it, and drives the most of it out past the ball check valve 12 and through the pipe 17 to a suitable storage 75 receptacle, not shown. When the pressure is relieved, the spring 8 returns the plunger 6 to its lowermost position; and when it reaches this position, the cylinder 1 is again filled with air through the inlet ports 11 by 80 atmospheric pressure.

It will of course be understood that when the cutoff valve is closed, there is no pressure communication between the air pump and engine cylinder, and that therefore the air 85 pump is out of action.

Changes and variations may be made in the specific structure by means of which the invention is carried into effect. The invention, therefore, is not to be restricted to the 100

precise details of the structure shown and described.

What is claimed is:

5. An air pump provided with a hollow stem adapted to be screwed into an engine cylinder to establish explosion pressure communication between said cylinder and said pump, a cutoff valve operative in said stem, and a priming device in communication with the

interior of said stem above said valve, said 10 pump having a cylinder with intake ports in its wall, a spring-pressed and pressure operated plunger working in said cylinder, and an outlet port in the cylinder head.

In testimony whereof, I have signed my 15 name to this specification.

WILFORD J. HAWKINS.
